REFINING HYDROCARBON OILS

Application filed June 16, 1928. Serial No. 285,822.

This invention relates to improvements in the manufacture of lubricating oils, and provides an improved method of producing lubricating oils from oils containing lubricating oil fractions, such as crude petroleum oils, topped crude oils, and the like. The invention is of special value and application in the manufacture of lubricating oils from certain types of crude oils or crude oil stocks of which the Gulf coast, south Texas, oils and the California oils may be taken as examples. In one aspect, this invention is an improvement upon the operation described in an application of Eugene C. Herthel and Harry L. Pelzer filed June 16, 1928, Serial No. 285,821.

In general, lubricating oils may be defined as oils heavier than gas oil, heavier than about 35° Bé., and having viscosities upwards of about 50 at 100° F. Saybolt universal.

There is a group of constituents, apparently characteristic of naphthalene base crude oils, which are extremely objectionable as components of lubricating oils in particular. These constituents are particularly objectionable in that they render unstable lubricating oils in which they are present. They also impair the quality of lubricating oils containing them in other respects, color for example.

As yet, this group of objectionable constituents has not been definitely identified. These objectionable constituents are themselves apparently of relatively low boiling point, yet they polymerize quite readily to form a tar or tarry substance. This polymerization is promoted, for example, by the presence of air or steam. With certain types of stocks, additional quantities of these objectionable constituents seem to be formed as long as the oil is maintained at elevated temperature, this effect increasing with temperature increase.

A number of schemes of procedure have been proposed intended to avoid the objectionable incidents of the presence of this group of objectionable constituents in lubricating oils, but these proposals have not been entirely satisfactory; in some cases because

of operating difficulties and in other cases because of failure to reach the real difficulty. Treatments of the raw stock preceding distillation have been proposed; such treatments are not effective with respect to objectionable constituents formed during distillation. Treatments of the raw stock supplied to and co-incidental with distillation have been proposed; in shell still distillations coke troubles have been encountered with crude stocks and in pipe still distillation corrosion difficulties have been encountered. In practice, the expedient most generally adopted has been to rerun the lubricating oil distillate fraction or fractions over caustic alkali but this scheme likewise is not entirely satisfactory; additional distillation operations are required, in some cases the lubricating oil distillate fraction must be rerun a second or third time, and rerunning subjects the lubricating oil to elevated temperatures over further prolonged periods of time. For the most part previous proposals further have been defective in the proper application of the principles of fractionation to accomplish the desired results.

Hitherto, the manufacture of lubricating oils has also almost uniformly involved refining with sulphuric acid, notwithstanding recognition of several disadvantages of such acid refining. In many cases this invention makes acid refining operations unnecessary.

The present invention provides an improved method of producing lubricating oils from oils containing lubricating oil fractions in which a treatment with caustic alkali and a treatment with an adsorbent agent are combined with a fractionating operation in a particularly advantageous manner, and in a manner particularly advantageous with respect to elimination of constituents of the objectionable group noted above in cases where such objectionable constituents are present.

In carrying out the present invention, a stream of stock containing lubricating oil constituents is flowed through a heating zone into a vapor separating zone, the stock is heated to a relatively low vaporizing temperature in the heating zone, the vapors separated in the vapor separating zone, includ-

ing the lubricating oil constituents, are caused to bubble through a hot liquid oil bath maintained alkaline by supplying caustic alkali thereto, the vapors including the lubricating oil constituents escaping from the hot alkaline bath are subjected to a fractionating operation in which higher boiling constituents are condensed, the remaining vapors including the lubricating oil constituents are taken off from this fractionating operation, a lubricating oil fraction or a series of lubricating oil fractions is condensed therefrom, and the lubricating oil fraction or fractions as condensed and while still at a temperature approximating 500-600° F. is contacted with a comminuted solid adsorbent such as fuller's earth, advantageously in the presence of a maintained atmosphere of a non-oxidizing, or better a reducing, gaseous medium.

Objectionable decomposition in the heating zone is avoided by limiting the time of passage of the oil through the heating zone and by limiting the temperature to which the oil is heated therein. In the vapor separating zone the vaporization of the lubricating oil constituents is with advantage promoted by the introduction of a distillation medium, superheated steam or some other superheated gaseous medium for example. The introduction of steam at this point has certain special advantages noted below. The vapor separation may be carried out co-incidently with the alkaline treatment; it is advantageous, however, to separate these operations first carrying out the vapor separation and taking off vapors including the lubricating oil constituents therefrom and then subjecting these vapors including the lubricating oil constituents to the alkaline treatment.

Where a distillation medium is supplied to the vapor separating operation, it is with advantage supplied at a temperature higher than that at which the oil leaves the heating zone.

By carrying out the heating and vaporizing operations as just described, the heating operation is carried out efficiently and vaporization of even the heavier lubricating oil constituents is effected while subjecting the oil containing these lubricating oil constituents to high temperatures for but a minimum time. A distillation medium may be passed through the heating zone with the raw stock but it is more advantageously introduced into the vapor separating zone where it is none the less effective in promoting vaporization of the lubricating oil constituents without interfering with the heating operation. Objectionable decomposition due to local overheating is avoided by maintaining rapid flow through the heating zone, by carrying out the vapor separation in an externally unheated zone, and by utilizing a distillation medium.

The hot alkaline treatment is with advantage carried out as described in an applica-

tion of Eugene C. Herthel and Harry L. Pelzer, filed June 16, 1928, Serial No. 285,820.

In the hot liquid alkaline oil bath, the lubricating oil constituents are subjected as vapors to intimate contact with caustic alkali. The caustic alkali neutralizes acidic constituents of the oil vapors and, apparently, also acts as a polymerizing agent promoting the polymerization of constituents of the objectionable group noted above. Steam used as a distillation medium in the vapor separation also assists in this polymerization and in some cases seems to make the caustic alkali more active. In any event, it is necessary, to secure the advantages of the invention, to fractionally condense higher boiling constituents from the vapors including the lubricating oil constituents escaping from the hot alkaline treatment before condensing the lubricating oil product or products. The high boiling constituents separated in this fractionating operation following the hot alkaline treatment and preceding condensation of the lubricating oil include reaction products of the hot alkaline treatment and the products of polymerization of any objectionable constituents present. Where the vapor separation and the alkaline treatment are carried out co-incidently, these reaction products and polymerization products may be separated with the residuum from the distillation; where the alkaline treatment is carried out separately from and subsequent to the vapor separation these reaction products and polymerization products may be separated as a separate caustic tar representing but a minor proportion of the total residuum.

The caustic alkali is advantageously supplied to the treating bath as a concentrated aqueous solution; when so supplied the water is evaporated from the bath leaving the alkali in suspension in a fine state of division throughout the bath. It is important that sufficient alkali be supplied to maintain the treating bath alkaline throughout the operation.

Following fractional condensation of high boiling constituents including these reaction products and polymerization products from the vapors including the lubricating oil constituents, the lubricating oil constituents may be condensed as a lubricating oil fraction or as a series of lubricating oil fractions. This separation of the lubricating oil product or products is also with advantage carried out by fractional condensation controlled to avoid condensation of any constituents of the objectionable group noted above remaining in low boiling form or formed in the vapor mixture after leaving the fractionating operation preceding the first separation of a lubricating oil product.

The lubricating oil fraction or fractions, as condensed and before any substantial

cooling below the temperature range in which the condensation is carried out, is then contacted with a comminuted solid adsorbent such as fuller's earth. This treatment is carried out as a unitary part of the complete operation. Where fuller's earth is used, the amount may vary, for example, from 1% to 10% on the weight of the condensate treated, about 8% usually being satisfactory.

10 Amounts of fuller's earth in excess of 30% usually make the suspension in the treating bath too thick to handle easily.

This treatment with a solid adsorbent is advantageously carried out by maintaining the comminuted solid adsorbent in suspension in a condensate bath to which the lubricating oil fraction is supplied as condensed, and the vapors supplied to the fractionating operation in which this lubricating oil fraction is condensed may with advantage be passed through this hot bath of condensate containing the comminuted solid adsorbent in suspension on their way to the condensing operation. The treated condensed lubricating oil fraction is discharged from this bath.

The treatment with a solid adsorbent is with advantage carried out as described in an application of James G. Stafford filed June 30, 1928, Serial No. 286,073.

The treatment with a solid adsorbent is advantageously carried out in the presence of a maintained atmosphere of a non-oxidizing, or better a reducing, gaseous medium.

35 The gaseous media useful for this purpose include hydrogen, carbon dioxide, nitrogen, natural gas and pressure still tail gases.

The comminuted solid adsorbent is maintained in an active condition by supplying fresh adsorbent to and discharging spent adsorbent from the treating bath as the operation proceeds. The comminuted solid adsorbent may be maintained in suspension in the treating bath by mechanical agitation, or

45 by the introduction of an extraneous gaseous medium, the treating gas for example, or by the introduction of the vapor mixture from which the constituents to be treated are condensed, or by a combination of these means.

50 The spent adsorbent is with advantage discharged in suspension in the treated condensed lubricating oil fraction discharged from the treating bath. The suspended solid adsorbent may be separated from the discharged lubricating oil fraction by filtering the oil while hot, for example at substantially the temperature at which it is discharged from the treating bath, or by first cooling the oil and then filtering the cooled oil.

55 The invention will be further described in connection with the accompanying drawings which illustrate, diagrammatically and conventionally, one form of apparatus for carrying out the invention.

The apparatus illustrated comprises a steam or gas superheater 1, an oil heater 2, a vapor separating tower 3, a combined treating and fractionating tower 4, a series of fractionating towers 5, 6, 7 and 8, the condenser 9, a series of coolers 10, 11, 12, 13, 14 and 15, and a series of hot oil filters 40, 41 and 42. Raw stock is supplied through connection 16 by means of a pump 31, flowed through oil heater 2 and thence into the lower end of vapor separating tower 3, unvaporized residue is discharged through cooler 10, the separated vapors escape from the upper end of tower 3 to the lower end of treating and fractionating tower 4 through connection 17, vapors escape from the upper end of tower 4 to the lower end of tower 5 and so on through towers 6, 7 and 8, the condensates separated in each of towers 5, 6, 7 and 8 are severally discharged through coolers 12, 13, 14 and 15 respectively, the condensates separated in towers 5, 6 and 7 may pass through filters 40, 41 and 42 on the way, and vapors escaping from the upper end of tower 8 are passed through condenser 9 where they are subjected to final condensation. Steam is supplied to the superheater 1 through connection 18, or other gaseous medium may be supplied through connection 19. The superheater 1 is connected through connection 20 with valved branch connections 43 and 44 for introduction of the superheated gaseous medium therefrom into the lower ends of towers 3 and 4 and through connection 20 and valved connection 61 with valved branch connections 45, 46, 47 and 48 for introduction of the superheated gaseous medium therefrom into the lower ends of towers 5, 6, 7 and 8. Connection 60 is provided to permit the supplying of a different gaseous medium to the lower ends of towers 5, 6 and 7 than is supplied from superheater 1; superheated steam may be supplied to the lower ends of towers 3 and 4 from superheater 1 and a treating gas such as natural gas or pressure still tail gases may be supplied to the lower ends of towers 5, 6, 7 and 8 through connection 60, for example. Cooling coils 23, 24, 25, 26, 27 and 28, are provided in the upper ends of the several towers; raw stock to be supplied to the operation, for example, may be circulated through these coils in series or in parallel on its way to the oil heater. Cooling coils 33, 34, 35, 36, 37 and 38, are also provided in the upper ends of the several towers; some supplementary refluxing or controlling cooling medium, water for example, may be circulated through these coils. By providing a pair of cooling coils in the upper end of each tower, as just described, the major part of the heat to be removed from the upper end of each tower can be absorbed in raw stock to be supplied to the operation and exact control can be had by regulation of the rate of circulation or the temperature

of the supplementary refluxing or cooling medium. The oil heater 2 may be of conventional pipe still construction. To avoid local overheating in particular, part of the escaping waste heating gases may be recirculated through the heating flues in admixture with fresh hot products of combustion from the firebox. The oil heater discharges into the vapor separating tower 3 at a point somewhat above its lower end to afford an opportunity for complete separation of vaporized constituents from unvaporized residual oil. Above this point of introduction, the vapors are subjected to a fractionating operation for the separation of very heavy constituents, 10 tars and the like. The vapor separating tower 3 may be by-passed by means of connection 32, and the vapor separation and the alkaline treating and fractionating operations carried 15 out together in tower 4, but this usually is less advantageous. Vapor connection 17 from the upper end of tower 3 to the lower end of tower 4 terminates in a normally submerged inlet pipe 21 for the introduction of 20 the vapors beneath the normal liquid level in the lower end of tower 4, and connection 22 is provided for the introduction into the vapors flowing from connection 17 and pipe 21 of caustic alkali. Vapor connection 29 25 from the upper end of tower 4 to the lower end of tower 5 also terminates in a normally submerged inlet pipe 49 for the introduction of the vapors beneath the normal liquid level in the lower end of tower 5. The vapor connections 30 and 32 from the upper end of 30 tower 5 to the lower end of tower 6 and from the upper end of tower 6 to the lower end of tower 7, respectively, are similarly arranged terminating in normally submerged 35 inlet pipes 50 and 51. A mechanical agitator 52 is also arranged beneath the normal liquid level in the lower end of each of towers 5, 6 and 7. Means 53 for supplying a comminuted solid adsorbent to the lower end 40 of towers 5, 6 and 7 are also provided. Vapors escaping from the upper end of tower 7 are discharged into tower 8 at a point somewhat above its lower end, the vapors being subjected to a fractionating operation above 45 the point of introduction and the condensate being subjected to a stripping operation for the separation of low boiling constituents below the point of introduction. A hot gaseous medium, superheated steam or other superheated gaseous medium from the superheater 1 or a hot treating gas, for example, 50 from connection 60 is supplied to the lower ends of towers 5, 6, 7 and 8 through connections 45, 46, 47 and 48 respectively to control, 55 in conjunction with controlled cooling at the upper ends of these towers, the fractionating operations carried out therein. Superheated steam or other hot gaseous medium is supplied to the lower end of tower 3 through connection 43, beneath the stripping section,

and to the lower end of tower 4 through connection 44 as a distillation medium as well as a control medium, and in the case of steam also as a treating agent. Connections 55, 56 and 57 are provided to permit the by-passing 70 of the submerged inlet pipes 49, 50 and 51 and connections 54, 58 and 59 are provided to permit the by-passing of the hot oil filters 40, 41 and 42. Tower 3 may be of open baffle construction or of so-called "bubble plate" 75 construction. Towers 4, 5, 6, 7 and 8 are with advantage of "bubble plate" or other construction adapted to secure close fractionation. The several towers, particularly towers 3 and 4, and the vapor connections 80 between them, are with advantage lagged or thermally insulated to minimize heat loss.

In carrying out the invention in the apparatus illustrated, the raw stock containing lubricating oil constituents, crude oil or topped crude oil for example, is forced through the oil heater 2 into the lower end of the fractionating tower 3 by means of pump 31. In the oil heater, the oil is heated to a limited vaporizing temperature, 700° F. for example, in a minimum of time. By using a pipe still to carry out this heating, the time during which the oil is passing through the heating operation is usually less in minutes than is the time in hours where shell stills are used for vaporization. The time of passage through the pipe still, for example, may be limited not to exceed 10 or 15 minutes, as compared to periods upwards of 10 hours in shell stills. In the fractionating tower 3, the lubricating oil constituents are separated or vaporized and separated from the unvaporized residual oil and the latter discharged through cooler 10. To promote this vaporization and separation, superheated steam, at temperatures in the 95 neighborhood of 800-900° F. for example, or other distillation medium, is supplied from the superheater 1 through connection 43. The operation of tower 3, as well as the operation of the remaining towers 4, 5, 6, 7 and 8, is controlled by regulated cooling at the upper end of the tower and by regulated heating at the lower end of the tower. The vapors containing lubricating oil constituents escaping from the upper end of tower 3 through line 17 are bubbled through a hot liquid oil bath maintained in the lower end of tower 4, being introduced beneath the liquid level thereof through pipe 21. This hot oil bath is maintained alkaline by supplying caustic alkali thereto 100 through connection 22 and pipe 21. This oil bath is maintained at a temperature sufficiently high to maintain in vapor phase the constituents of the desired lubricating oil products. The vapors escaping from this treating bath, including the lubricating oil constituents, are subjected to closely controlled fractionation as they flow upwardly through tower 4. The liquid treating bath in the lower 105 end of tower 4 is with advantage maintained 110

110

115

120

125

130

135

of substantially constant volume as the operation proceeds. Any tendency of the bath to decrease in volume may be counteracted by supplying the caustic alkali at a lower temperature, by cooling or increasing the cooling of the vapors in the upper end of the tower, by decreasing the rate of liquid discharge through cooler 11, or by decreasing the rate at which the heating medium is supplied to the lower end of the tower. Any tendency of the bath to increase in volume may be counteracted by supplying the caustic alkali at a higher temperature, by decreasing the cooling of the vapors in the upper end of the tower, by increasing the rate of liquid discharge, or by increasing the rate at which the heating medium is supplied to the lower end of the tower. The vapors in the upper end of the tower 4 are cooled sufficiently to condense all tarry constituents or other high boiling constituents, including reaction products of the alkaline treatment, not suitable as components of the desired lubricating oil products. In the towers 5, 6, 7 and 8, the vapors escaping from the upper end of tower 4 are subjected to fractional condensation to separate and condense therefrom a series of progressively lighter and less viscous oil products. For example, a heavy lubricating oil may be condensed in tower 5, an intermediate lubricating oil in tower 6, a light lubricating oil in tower 7 and a gas oil in tower 8. A bath of condensate is maintained in the lower end of each of towers 5, 6 and 7 and a comminuted solid adsorbent such as fuller's earth of 100-mesh or finer is supplied to and maintained in suspension in these condensate baths. The vapors from the preceding tower are introduced beneath the normal liquid level of each of the baths in the lower ends of towers 5, 6 and 7 and bubbled therethrough, thus assisting in maintaining the adsorbent in suspension in the oil bath at the same time bringing the vapors into intimate contact with the oil bath. If this action is insufficient, in conjunction with the similar action of any gas introduced through connections 45, 46 and 47, to maintain the adsorbent in suspension in the oil bath, mechanical agitation is supplied by means of agitators 52. The oil baths containing the suspended comminuted solid adsorbent in the lower ends of towers 5, 6 and 7 are with advantage maintained at temperatures in the general range of 500-600° F. while at atmosphere of a non-oxidizing, or better a reducing, gaseous medium is maintained by supplying such treating gas through connections 45, 46 and 47 at a rate sufficient to maintain the baths saturated therewith. Where such a treating gas is supplied to the lower ends of towers 5, 6 and 7, it is with advantage supplied hot, at temperatures in excess of the temperatures at which the vapors from the preceding tower enter the lower end of each tower, to permit its use as a controlling medium. Such a treating gas may also be used as a distillation medium in towers 3 and 4 or it may be supplied only to towers 5, 6, 7 and 8 and superheated steam or other superheated gaseous medium from the superheater 1 supplied to the lower ends of towers 3 and 4. It is usually most convenient to use the same gaseous medium as a controlling medium in tower 8 as is used in the immediately preceding towers 5, 6 and 7. As the operation proceeds, treated oil containing the adsorbent in suspension is discharged from the condensate baths in the lower ends of towers 5, 6 and 7 through filters 40, 41 and 42 for the removal of the adsorbent and the filtered oil then discharged through coolers 12, 13 and 14. Additional adsorbent is supplied through means 53 as the operation proceeds. Vapors escaping uncondensed from tower 8 may be condensed as a naphtha in the condenser 9.

The following example will illustrate an operation embodying the invention as carried out in apparatus of the type illustrated: Gulf coast crude oil is supplied to the oil heater 2 at a rate of about 10,500 gallons per hour and discharged from the oil heater at a temperature of about 750-800° F. An aqueous solution of caustic soda, 25° Bé., is supplied to the lower end of tower 4 at a rate of about 150-250 gallons per hour. The temperature at the bottom of tower 3 is maintained at about 720° F. and at the top at about 700° F.; the temperature at the bottom of tower 4 is maintained at about 690° F. and at the top at about 670° F.; the temperature at the bottom of tower 5 is maintained at about 650° F. and at the top at about 620° F.; the temperature at the bottom of tower 6 is maintained at about 600° F. and at the top at about 540° F.; the temperature at the bottom of tower 7 is maintained at about 500° F. and at the top at about 430° F.; and the temperature at the bottom of tower 8 is maintained at about 400° F. and at the top at about 330° F. Crude oil to be distilled is circulated through the cooling coils in the upper ends of the several towers and thus preheated. Superheated steam or superheated pressure still tail gases or superheated natural gas, for example, at a temperature in the neighborhood of 900° F. is supplied to the lower ends of towers 3 and 4 at rates regulated to maintain the temperatures mentioned. Superheated steam at 900° F. is, for example, supplied to the lower ends of towers 3 and 4 at a combined rate approximating 1-3 pounds per gallon of crude oil supplied to the heater. Pressure still tail gases or natural gas, for example, at a temperature in the neighborhood of 700-900° F. is supplied to the lower ends of towers 5, 6, 7 and 8 at rates regulated to maintain the temperatures mentioned. Fuller's earth is supplied to the lower end of tower 5 at a rate of about 500-1000 pounds per hour, to the lower end of tower 6 at a rate of about 1000-1800

pounds per hour and to the lower end of tower 7 at a rate of about 800-1500 pounds per hour. Crude oil may thus be separated, for example, into a residuum, about 10% discharged through cooler 10, a caustic bottoms, about 3%, discharged through cooler 11, a heavy lubricating oil, about 10%, discharged through cooler 12, an intermediate lubricating oil, about 20%, discharged through cooler 13, a light lubricating oil, about 13%, discharged through cooler 14, a gas oil, about 35-40%, discharged through cooler 15, and a naphtha discharged through condenser 9.

The operation just described makes possible the direct production from Gulf coast crudes, for example, of distilled lubricating oil products which, without further refining treatment, and in particular without acid refining treatment, are of good color and stability. Stable lubricating oils having viscosities as high as 900 at 100° F. or higher and of 1½ color or better may be so produced. The lubricating oils so produced are of high quality with respect to all the usual requirements, Conradson carbon test, emulsibility test, etc.

We claim:

1. In the manufacture of distilled lubricating oils from petroleum stocks, the improvement which comprises flowing a stream of the stock through a heating zone into a vapor separating zone, heating the stock to a vaporizing temperature in the heating zone, separating the vapors from the liquid oil in the separating zone, passing the vapors separated in the vapor separating zone through a hot liquid oil bath maintained alkaline by supplying caustic alkali thereto, subjecting the vapors escaping from the hot alkaline oil bath to a fractionating operation and condensing high boiling constituents therein, taking off vapors from the fractionating operation and condensing a lubricating oil fraction therefrom, and subjecting the lubricating oil fraction as condensed and while still at elevated temperature to contact with a comminuted solid adsorbent.

2. In the manufacture of distilled lubricating oils from petroleum stocks, the improvement which comprises flowing a stream of the stock through a heating zone into a vapor separating zone, heating the stock to a vaporizing temperature in the heating zone, separating the vapors from the liquid oil in the separating zone, passing the vapors separated in the vapor separating zone through a hot liquid oil bath maintained alkaline by supplying caustic alkali thereto, subjecting the vapors escaping from the hot alkaline oil bath to a fractionating operation and condensing high boiling constituents therein, taking off vapors from the fractionating operation and condensing a lubricating oil fraction therefrom, and subjecting the lubricating oil fraction as condensed and while still

at a temperature approximating 500-600° F. to contact with a comminuted solid adsorbent.

3. In the manufacture of distilled lubricating oils from petroleum stocks, the improvement which comprises flowing a stream of the stock through a heating zone into a vapor separating zone, heating the stock to a vaporizing temperature in the heating zone, separating the vapors from the liquid oil in the separating zone, passing the vapors separated in the vapor separating zone through a hot liquid oil bath maintained alkaline by supplying caustic alkali thereto, subjecting the vapors escaping from the hot alkaline oil bath to a fractionating operation and condensing high boiling constituents therein, taking off vapors from the fractionating operation and condensing a lubricating oil fraction therefrom, and subjecting the lubricating oil fraction as condensed and while still at elevated temperature to contact with a comminuted solid adsorbent in the presence of a maintained atmosphere of a non-oxidizing gas.

4. In the manufacture of distilled lubricating oils from petroleum stocks, the improvement which comprises flowing a stream of the stock through a heating zone into a vapor separating zone, heating the stock to a vaporizing temperature in the heating zone, separating the vapors from the liquid oil in the separating zone, passing the vapors separated in the vapor separating zone through a hot liquid oil bath maintained alkaline by supplying caustic alkali thereto, subjecting the vapors escaping from the hot alkaline oil bath to a fractionating operation and condensing high boiling constituents therein, taking off vapors from the fractionating operation and condensing a lubricating oil fraction therefrom, and subjecting the lubricating oil fraction as condensed and while still at elevated temperature to contact with a comminuted solid adsorbent in the presence of a maintained atmosphere of a reducing gas.

5. In the manufacture of distilled lubricating oils from petroleum stocks, the improvement which comprises flowing a stream of the stock through a heating zone into a vapor separating zone, heating the stock to a vaporizing temperature in the heating zone, introducing superheated steam into the vapor separating zone, separating the vapors from the liquid oil in the separating zone, passing the vapors separated in the vapor separating zone through a hot liquid oil bath maintained alkaline by supplying caustic alkali thereto, subjecting the vapors escaping from the hot alkaline oil bath to a fractionating operation and condensing high boiling constituents therein, taking off vapors from the fractionating operation and condensing a lubricating oil fraction therefrom, and subject-

ing the lubricating oil fraction as condensed and while still at elevated temperature to contact with a comminuted solid adsorbent in the presence of a maintained atmosphere of a non-oxidizing gas.
